UNITED STATES PATENT OFFICE

100,256

DESIGN FOR A COMBINED APPLICATOR AND MASSAGE BRUSH

Charles M. Butler, Chicago, Ill.

Application April 4, 1936, Serial No. 61,961

Term of patent 14 years

To all whom it may concern:

Be it known that I, Charles M. Butler, a citizen of the United States, residing at Chicago, in the county of Cook and State of Illinois, have invented a new, original, and ornamental Design for a Combined Applicator and Massage Brush, of which the following is a specification, reference being had to the accompanying drawing, forming part thereof.

I claim:

The ornamental design for a combined applicator and massage brush, as shown.

CHARLES M. BUTLER.
